RAILWAY CAR

Francis T. Burgess, Maplewood, Mo., assignor to
American Car and Foundry Company, New
York, N. Y., a corporation of New Jersey

Application March 28, 1946, Serial No. 657,870

16 Claims. (Cl. 105—315)

1

This invention relates to railway sleeping cars and has as its object to provide in railway cars of standard dimensions the greatest number of private single occupancy rooms having beds and toilet facilities, consistent with passenger comfort and convenience.

For passenger comfort and convenience it is desirable to provide ample head space for the occupant of the room when he is in the standing, sitting, or reclining position. However, an individual in the reclining or sleeping position does not require an equivalent amount of vertical clearance above his lower limbs and extremities.

In this invention I attempt to achieve the above stated object by arranging the rooms, which are located in the spaces between the partitions defining a central aisle and the outer walls of the car, on two floor levels. To take full advantage of the fact that the lower extremities of a person in the sleeping position do not require much vertical space, and to insure adequate and ample head space in the standing and sitting areas of the room I cause the end portions of the upper room to extend above a relatively unused end portion of each of two lower rooms, and utilize the overhung end portion of each of the lower rooms as a bed storage compartment during the daytime and to provide leg room for the occupant of the room when in the sleeping position. The overhanging end portions of the upper room are used respectively, as a seat and for the same purpose as the overhung end portions of the lower rooms.

Additional height is provided for the portions of the car interior in which the rooms are located by depressing the car floor to the minimum height above the rail consistent with standard railroad practice.

A further object of this invention is to provide a bed substantially equal in length to the room for each of the rooms and retractable from the standing and sitting areas of the rooms and adapted to be stored when not in use in the relatively small overhanging and overhung portions of each of the rooms.

The above mentioned objects as well as additional features of the invention will be more fully understood from the following detailed description, throughout which reference is made to the accompanying drawings, in which:

Figure 1 is a general view of a railway car interior in perspective, and showing an arrangement of rooms and an underframe and floor structure in accordance with the invention;

Fig. 2 is a longitudinal sectional view of three

2

rooms in a railway car designed according to the invention, as viewed with an outer wall of the car removed;

Fig. 3 is a longitudinal sectional view of the same three rooms as viewed with a central aisle partition removed;

Fig. 4 is a transverse sectional view taken along the line 4—4 of Figures 2 and 3;

Fig. 5 is a transverse sectional view taken along the line 5—5 of Figures 2 and 3;

Fig. 6 is a transverse sectional view along the line 6—6 of Figure 2;

Fig. 7 is a transverse sectional view taken along the line 7—7 of Figure 2;

Fig. 8 illustrates a grooved guideway for the bed of the upper rooms;

Fig. 9 illustrates a slightly different grooved guideway for the bed of the lower rooms;

Fig. 10 shows a catch locking the bed in the horizontal extended position;

Fig. 11 shows the same catch released, the hinges joining the bed side rails open;

Fig. 12 shows a vertical bed guideway, its groove and slide block;

Fig. 13 shows the lower end of a bed with bearing fixtures attached to the side rails and a rod extending through the bearing fixtures and having at one end one of the slide-blocks of the vertical guideway;

Fig. 14 is a detail view of a spring buffer provided to initiate upward movement of the slide blocks in the vertical guideways;

Fig. 15 is an end view of the foot section of the bed showing a cross sectional view of the curved guideway and the roller traveling therein.

In all figures, the numeral 1 represents the longitudinal center sill of a railway car which supports spaced transverse members 2 such as I-beams, both cooperating to form a rigid car underframe. On the upper surface of the upper flange of the transverse members 2 is laid a narrow floor 3 extending the full length of the car. On the upper surface of the lower flange of transverse members 2 are laid depressed floor sections 4, each being the full width of the car. Ceiling 5 is separated from roof 6 by a space 7 adapted for use as an air conditioning duct. Interior spaced longitudinal partitions 8 define a central aisle. The spaces defined laterally by longitudinal partitions 8 and car sidewalls 9 are longitudinally divided in the following manner.

Lower room 10 is defined longitudinally in the space by transverse partitions 11 and 12. Adjacent to lower room 10, an upper room 13 is defined as follows. Transverse partition 12 and

hollow transverse partition 18 form the end walls. Transverse partition 15, extends vertically less than half the distance from car floor 4 to car ceiling 5, and extends inwardly from car sidewall 9. A short longitudinal partition 16, equal in height to transverse partition 15, extends between transverse partitions 12 and 15. The area bounded by the upper edges of partitions 12, 15 and 16, and car sidewall 9 is covered by horizontal partition 17. An elevated floor 19 at a lower level than horizontal partition 17 and at a higher level than aisle floor 3 fills the area defined by partitions 8, 12, 15, 16, 18 and car wall 9.

A second lower room 20 is defined by partitions 8, 18, and 11 and car sidewall 9.

The recess 23, defined by partitions 12, 15, 16, 17, and car sidewall 9 communicates with lower room 10 by means of a rectangular opening 24 in transverse partition 12.

The interior of hollow transverse partition 18 is divided vertically into recesses 25, 26, and 27. Recesses 25 and 26 communicate with upper room 13 by means of openings 28 and 29, in partition 18. Recess 27 communicates with lower room 20 through opening 30 in partition 18.

Upper room 13 utilizes horizontal partition 17 as a seat; lower rooms 10 and 20 are provided with transverse seats 31. All upper and lower rooms have seat cushions 32, hinged backrests 33 and a conventional toilet unit comprising enclosed hoppers 34, folding lavatories 36, cabinets 37, shaving mirrors 38 and shaving lamps 39. Luggage racks 41 are also provided in lower rooms.

Openings 40 provide communication between the central aisle and rooms 10, 13, 20. These openings are closed by conventional type sliding doors 63 which are adapted to slide from the closed position into a recess in longitudinal partition 8. A partially recessed step 42 located beneath opening 40 into the upper room provides access from central aisle 14 to upper room 13.

Within each of the recesses 23, 26, and 27 is a folding bed comprising head section 47 and foot section 51. The head section 47 is formed by a headboard 48, two side rails 49 and 50, and a bottom 51. When stored in the bed recess, head section 47 is in a vertical position, with the headboard 48 uppermost, and bottom 51 against the partition, 12, or 18 which separates the bed recess from the room with which it communicates.

A door 43 in openings 24, 28, and 29 forms a part of the bottom 51 of head section 47. Door 43 has flanges 44 and 45 on its upper and lower edges. A downward opening groove 52 is formed edge flange 45, the lower edge of door 43, and bottom 51. The lower edge 53, of rectangular openings 24, 28, and 29 fits into groove 52, and combines with it to form a detachable hinge.

A spring operated, manually released catch 46 of conventional design projects through headboard 48, and engages the inner side of transverse partition 12, or 18, combining with flange 44 on the outer side of door 43 to secure door 43 and head section 47 in the vertical or closed position. T-shaped handle 65, projecting outwardly through door 43 is rotated to release catch 46.

The bed foot section 57 comprises a footboard 75, siderails 55 and 56, and a bottom 76. Foot section 57 is stored in recess 23, 26 or 27 in a nearly vertical position, with the footboard 75 uppermost. Siderails 49 and 50 of head section 47 are flexibly joined to side rails 55 and 56 of foot section 57 by hinges 54.

To the footboard end of foot section 57 are

attached bearings 58, through which pass a cylindrical rod 59. Guide followers 60, on the end of cylindrical rod 59 fit in and are adapted to travel vertically in the vertical grooved guideways 61. Vertical grooved guideways 61 are secured to each of the sidewalls of the bed recess, adjacent to the rear wall of the bed recess.

A grooved guideway 64 is secured to car sidewall 9 and extends in a curve from the lower portion of the bed recess into the adjacent room, where it terminates in a short vertical slot 66.

A roller 63, supported by bearing 62 at the hinged end of the outer siderail 56, fits in and is adapted to travel in guideway 64.

A flat metal catch 67, having a slot 68 at one end, and pivotally attached to siderail 57 near its hinged end, is adapted to be manually engaged with a projection 69 on siderail 49 when the bed is in the extended position, as hereinafter described.

Spring buffers, generally indicated at 74 are provided and are fastened to the inner transverse wall of recesses 23, 26 and 27 immediately adjacent to vertical grooves 61. Spring buffer 74 is shown in detail in Fig. 14, wherein channel 70 is shown attached to the recess wall. Through a perforation in the flanges of channel 70 extends pin 71, to the upper end of which is attached spring retainer disk 72. Compression spring 73, resting on the upper surface of channel 70 acts upwardly against spring retainer disk 72.

The conversion of rooms 10, 13 and 20 into sleeping rooms is accomplished by folding back rest 33 to the horizontal position. Handle 65 is turned, thereby releasing spring catch 46. Using handle 65, the operator pulls door 43 and the bed section 47 outward and upward. Bed section 57 follows bed section 47, its remote end being guided by vertical grooves 61, and its upper hinged end by curved groove 64 until it reaches an approximately horizontal position. When bed section 57 reaches this position, the hinged end must be forced downward, thereby causing roller 63 to drop into vertical slot 66 at the end of curved groove 64, thereby securing bed section 57 in the horizontal position. When bed section 57 is thus secured bed section 47 is allowed to come to rest in a horizontal position on the upper surface of downfolded back rest 33, as shown in Fig. 3. Catch 67 on bed side rail 56 is manually rotated until its slot 68 is engaged by projection 69 on siderail 50, thereby locking bed sections 47 and 57 together in a horizontal position so that they form a bed extending the combined lengths of the room 10, 13 or 20 and recess 23, 26 or 27.

The rooms are converted from sleeping to sitting rooms in the following manner. Catch 67 on bed siderail 56 is manually rotated until it is in the open position as shown in Fig. 11. Bed section 47 is swung upward and lifted vertically until roller 63 is out of vertical slot 66. Spring buffers 74 then begin to act upwardly against the lower surfaces of bearing fixtures 53, thereby causing the lower end of bed section 57 and guide blocks 60 to move upwardly in vertical grooves 61. By pushing forward and downward on bed section 47, utilizing handle 65 as a handhold, the bed sections 47 and 57 will be forced into their stored position in recess 23, 26, or 27, and will be retained therein by spring operated catch 46.

While only the preferred embodiment of my invention has been described and illustrated herein, it is to be understood that the exclusive

use is contemplated of all forms of the invention which come within the scope of the appended claims.

I claim:

1. In a railway car having a central aisle floor, two lower rooms having a floor level below said aisle floor, an upper room having its floor level higher than said aisle floor, said upper room being interposed between said lower rooms and having end portions extending above an extremity of each of said lower rooms, and a bed extending substantially the entire length of each of said rooms, said beds being retractable respectively into one end portion of said upper room and into the extremities of said lower rooms adjacent said upper room.

2. In a railway car having a central aisle floor, spaced longitudinal partitions defining a central aisle, outer walls, a roof, two lower rooms having a floor level lower than the floor of said aisle in each space defined by one of said longitudinal partitions and one of said car walls, an upper room having its floor level higher than the floor of said aisle, said upper room being disposed longitudinally between said lower rooms and having end portions extending above an end portion of each of said lower rooms, and a longitudinally extending bed in each of said upper and lower rooms retractable respectively into one end portion of said upper room and into the end portions of said lower rooms adjacent said upper room, said bed extending the entire length of each of said rooms.

3. In a railway car having a central aisle floor, spaced longitudinal partitions defining a central aisle, outer walls, a roof, two lower rooms having a floor level lower than the floor of said aisle and situated in the space defined by one of said longitudinal partitions and one of said outer walls, an upper room having its floor level higher than the floor of said aisle, said upper room being disposed longitudinally between said lower rooms, a fixed transverse seat for said upper room, the space under said fixed transverse seat forming a portion of the first of said lower rooms, a hollow partition separating said upper room from the second of said lower rooms, an upper recess in said hollow partition forming a portion of said upper room, and a lower recess in said partition forming a portion of the second of said lower rooms, each of said lower rooms containing a fixed transverse seat, each of said upper and lower rooms containing a toilet and lavatory, and a bed extending the entire length of each of said upper and lower rooms, said beds being retractable respectively into the space under said fixed transverse seat of the upper room and into said upper and lower recesses.

4. In a railway car having a central aisle floor, longitudinal partitions defining a central aisle, outer walls, a roof, two lower rooms having a floor level lower than the floor of said aisle and situated in a space defined by one of said longitudinal partitions and one of said outer walls, an upper room having its floor level higher than the central aisle floor, said upper room being disposed longitudinally between said lower rooms, each of said rooms having a fixed transverse seat, a single, transverse partition separating said upper room from the first of said lower rooms, the fixed transverse seat of said upper room being arranged adjacent said single partition, a toilet and lavatory in each of said rooms, the space under the fixed transverse seat of said upper

room communicating with and forming a portion of the first of said lower rooms, a hollow partition separating said upper room from the second of said lower rooms, an upper recess in said hollow partition communicating with and forming a portion of said upper room, a lower recess in said hollow partition communicating with and forming a part of the second of said lower rooms, a bed extending substantially the entire length of each of said rooms, a bed in the first of said lower rooms retractable from the standing and sitting area of said lower room into the space under the seat of said upper room, a bed in said upper room retractable from the standing and sitting areas of said upper room into said upper recess in said hollow partition, and a bed in the second of said lower rooms retractable from the standing and sitting areas of said room into said lower recess in said hollow partition.

5. In a railway car, longitudinal partitions defining a central aisle having a floor at the customary level, outer side walls, a roof, two lower rooms having a floor level lower than the floor of the central aisle and occupying the space defined by one of said longitudinal partitions and one of said outer side walls, an upper room having its floor level higher than the floor of the central aisle, each of said rooms having a fixed transverse seat, a toilet, and lavatory, the space under the fixed transverse seat of said upper room communicating with and forming a portion of the first of said lower rooms, a hollow partition separating said upper room from the second of said lower rooms, the toilet and lavatory of said upper room and said second lower room being disposed, respectively, against said longitudinal partition and on opposite sides of said hollow partition, upper and lower recesses in said hollow partition communicating, respectively, with said upper room and the second of said lower rooms, a bed in each of said rooms extending substantially the full length of each of said rooms, said beds being retractable, respectively, into the space under the fixed transverse seat of the upper room and into the upper and lower recesses in said hollow partition.

6. In a railway car having an underframe including a longitudinal center sill and spaced transverse members, longitudinal partitions defining a central aisle, a floor for said central aisle supported on the upper surface of said underframe, two lower rooms each having a floor depressed between adjacent transverse members, an upper room having an elevated floor, said upper room being disposed longitudinally between said lower rooms and overhanging an end portion of each of said lower rooms, each of said rooms having a fixed transverse seat and a toilet and lavatory, and a bed extending substantially the entire length of each of said rooms, said beds being retractable respectively into an overhanging and the overhung portions of each of said rooms.

7. In a railway car having a central aisle floor, two lower rooms having a floor level lower than the central aisle floor, an upper room having a floor level higher than the central aisle floor, said upper room being disposed between said lower rooms and overhanging an end portion of each of said lower rooms, a bed stored in an overhanging and the overhung portions of each of said rooms and extensible the full length of said rooms, and a fixed transverse seat at the opposite end of each of said rooms.

8. In a railway car having a central aisle floor,

two lower rooms having a floor level lower than the central aisle floor, an upper room having a floor level higher than the central aisle floor, said upper room being disposed between said lower rooms and overhanging an end portion of each of said lower rooms, a folding bed stored in an overhanging and the overhung portions of each of said rooms, transverse partitions enclosing an overhanging and the overhung portions of said rooms, a door in each of said transverse partitions, said door being integral with one section of said folding bed and detachably hinged at its lower edge to said transverse partition, said folding bed also having a second section hinged to the first section, said bed being extensible the full length of said room.

9. In a railway car, a central aisle floor, lower rooms arranged at each side of said central aisle floor and having their floor below said central aisle floor, an upper room arranged with its floor above said central aisle floor and interposed longitudinally between each pair of said lower rooms, a bed recess formed at the end of each room, said bed recess of each upper room extending above the bed recess of one adjacent lower room, and said bed recess of the other adjacent lower room extending below said upper room, and a folding bed enclosed in each of said bed recesses, said folding bed being extensible substantially the combined length of said room and said bed recess and forming when enclosed a portion of the room wall structure, a toilet and lavatory in each room adjacent the end having a bed recess, and a fixed transverse seat in the opposite end of each room.

10. In a railway car, a central aisle floor, lower rooms arranged at each side of said central aisle floor and having their floor below said central aisle floor, an upper room arranged with its floor above said central aisle floor and interposed longitudinally between each pair of said lower rooms, a fixed transverse seat in each of said rooms, and a bed recess formed at the end of each room, said bed recess of each upper room extending above the bed recess of one adjacent lower room, and said bed recess of the other adjacent lower room extending below the fixed transverse seat of said upper room, and a luggage shelf for said upper room in the space above said upper bed recess, and a folding bed enclosed in each of said bed recesses, said folding bed being extensible substantially the combined length of each of said rooms and its bed recess and forming when enclosed a portion of the room wall structure.

11. In a railway car, spaced longitudinal partitions defining a central aisle, a central aisle floor, lower rooms arranged at each side of said central aisle and communicating with said central aisle, said lower rooms having their floor below said central aisle floor, an upper room communicating with said aisle and arranged with its floor above said central aisle floor, said upper room being interposed longitudinally between each pair of lower rooms, and a bed recess formed at the end of each room, said bed recess of each upper room extending above the bed recess of one adjacent lower room, a luggage shelf for said upper room in the space above said upper bed recess, said bed recess of the other adjacent lower room extending beneath the fixed transverse seat of said upper room, a luggage shelf in the bed recess end of each lower room, and a folding bed in said bed recess, said folding bed including a portion of the room wall structure and being

extensible to the combined length of the room and bed recess.

12. In a railway car, a central aisle, spaced longitudinal partitions defining said central aisle, a plurality of lower rooms arranged in pairs at each side of said central aisle and communicating with said aisle, an upper room interposed between each pair of lower rooms, transverse partitions defining said upper and lower rooms, said lower rooms having their floor below said central aisle floor, said upper rooms arranged with their floors above said central aisle floor, a transverse fixed seat in each of said rooms, a bed recess formed at the end of each room and communicating with said room, said bed recess of each upper room extending above the bed recess of an adjacent lower room, the bed recess of the other adjacent lower room extending below the fixed transverse seat of said upper room, a luggage shelf for said upper room in the space above said upper room bed recess, a toilet and lavatory in the bed recess end of each room adjacent said longitudinal partition, a toilet and lavatory in the bed recess end of each room adjacent the longitudinal partition, a luggage shelf extending transversely across the bed recess end of each lower room, a fixed transverse seat extending substantially across the opposite end of each lower room and a folding bed in each bed recess, said folding bed including a portion of one of said transverse partitions and being extensible substantially the combined length of said room and said bed recess.

13. In a railway car, a plurality of lower rooms arranged longitudinally in pairs, an upper room interposed between each pair of said lower rooms, a central aisle floor below the floor level of said upper room, and above the floor level of said lower rooms, a bed recess formed at one end of each room, said upper room and its bed recess extending above the bed recesses of the two adjacent lower rooms, and a longitudinally folding bed in each bed recess, said folding bed comprising two hinged sections, one of said sections forming a portion of the room wall structure, means for extending each bed substantially the combined length of a room and its bed recess, and means for locking said bed in the extended position.

14. In a railway car, a central aisle floor, lower rooms arranged in pairs at each side of central aisle floor and having their floor below said central aisle floor, an upper room interposed between said lower rooms and having its floor above said central aisle floor, a bed recess formed at an end of each of said rooms and forming a part of said room, the end portions of said upper room extending above the bed recesses of the two adjacent lower rooms, and a folding bed in each bed recess, said folding bed comprising a head section and a foot section, said head and foot sections being stored vertically in each bed recess and being flexibly joined at their adjacent end portions, said head section including a portion of the room wall structure, said folding bed being extensible substantially the entire length of each room and its bed recess.

15. In a railway car, longitudinal partitions defining a central aisle, outer side walls, a roof, two lower rooms laterally defined by one of said longitudinal partitions and one of said outer side walls, an upper room having its floor at a higher level than said lower rooms, each of said rooms having a fixed transverse seat, a toilet, and lavatory, the space defined beneath the fixed trans-

verse seat of said upper room communicating with the first of said lower rooms, a hollow partition separating said upper room from the second of said lower rooms, beds extending substantially the entire length of each of said rooms, the bed of the first of said lower rooms retractable into the space beneath the seat of said upper room, the bed of said upper room and said second lower room being retractable into said hollow partition.

16. In a railway car having a central enclosed aisle, two lower rooms disposed at one side of said central aisle, an upper room, said upper room being disposed between said lower rooms and overhanging an end portion of each lower room, a folding bed stored in an overhanging and the overhung portions of each of said rooms, transverse partitions enclosing an overhanging and the overhung portions of said rooms from the sitting and standing areas of said rooms, a door

10

5 in each of said transverse partitions, said door being integral with one section of said folding bed and detachably hinged at its lower edge to said transverse partitions, said folding bed also

having a second section hinged to the first section, said bed being extensible the full length of

said room.
